Primary Examiner — Kevin K Rudzinski*Assistant Examiner* — Richard E Yenchesky(74) *Attorney, Agent, or Firm* — Gardner, Linn, Burkhardt & Ondersma LLP(57) **CLAIM**

The ornamental design for a filter for a wash tub, as shown and described.

DESCRIPTION

FIG. 1 is a top perspective view of a filter for a wash tub; FIG. 2 is a bottom perspective view thereof; FIG. 3 is a top plan view thereof; FIG. 4 is a front elevation thereof; FIG. 5 is a left side elevation thereof; FIG. 6 is a right side elevation thereof; FIG. 7 is a rear elevation thereof; and, FIG. 8 is a bottom plan view thereof.

The broken lines in the drawings are for the purpose of illustrating portions of the filter for a wash tub that form no part of the claimed design.
